VIBRATOR CIRCUIT

Paul F. G. Holst, Oaklyn, N. J., assignor to Radio Corporation of America, a corporation of Delaware

Application October 31, 1939, Serial No. 302,186

10 Claims. (Cl. 175—365)

The present invention relates to a vibrator circuit wherein a vibratory contact device is utilized to make and break electrical circuits in connection with a transformer for converting direct current into alternating current or into direct current of a higher voltage, and has for its primary object to provide an improved vibrator circuit of the character referred to for full wave operation in connection with relatively high input voltages and at relatively high frequencies.

It is also an object of the present invention to provide an improved full wave vibrator circuit for the primary of a vibrator transformer whereby high input voltages may be employed without arcing between contacts when operated with narrow air gaps in connection with voltages above the normal arcing potential therefor.

The invention will be better understood from the following description when considered in connection with the accompanying drawing, and its scope is pointed out in the appended claims.

Referring to the drawing, the figure is a schematic diagram of a vibrator circuit embodying the invention, and including a power transformer 5 having suitable secondary windings 6, 7 and 8 for alternating current supply to utilization apparatus, not shown, and an energizing or primary winding 9 of the balanced or full wave type having a center tap 10 and two end terminals 11 and 12, the latter terminals being connected with two oppositely disposed fixed vibrator contacts 13 and 14, respectively, through leads 15 and 16.

The center terminal 10 is connected with one side of a supply line 17, the opposite side 18 of which is connected with a second pair of oppositely disposed contacts 19 and 20 positioned adjacent to the contacts 13 and 14 and in spaced relation to contacts 21 carried by a vibratory reed or armature element 22. Similar contacts 24 are provided on the reed between the contacts 13 and 14, the two sets of contacts being carried by the free end of the reed 22, while the opposite end thereof is fixed as indicated by the supporting member 25.

As the reed vibrates in the limited space between the pairs of contacts 19—20 and 13—14, it forms a moving electrical bridge connection engaging first the contacts 13 and 19 and then the contacts 20 and 14, thereby providing a connection first between the supply lead 18 and the input lead 15 and then between the supply lead 18 and the input lead 16, causing current to flow alternately through each half of the winding 9,

from the terminals 11 and 12 to the terminal 10.

The primary circuit may thus be supplied with energy at high voltage, such as a voltage indicated at E between the leads 17 and 18, and the movement of the free end of the reed may be relatively short to permit high frequency operation with relatively narrow air gaps between the pairs of contacts, for the reason that the movable contact element constituted by the reed 22 forms a bridge with two air gaps in series for breaking the electrical circuits with the primary winding.

Furthermore, the reed 22 does not require any external electrical connection and may be insulated from the entire electrical circuit since it is in contact with the circuit only when moved to the closed position in either direction.

The use of two air gaps in series as shown reduces the voltage across each gap to a value below that of the supply and doubles the speed of the break of the electrical circuits, thereby minimizing arcing and burning of the contacts normally encountered in the operation of vibrator systems and as would be difficult to avoid in the operation of such high frequency systems with relatively high voltages which exceed the normal arcing potential of the usual contacts.

The vibrator armature element may be actuated by the short circuited coil method as shown, which in the present example comprises a vibrator magnet winding 26 having a core 27 associated with an armature bar 28 on the reed for causing the bar 28 to move in the direction of the core 27 when the coil is energized.

The coil 26 is energized across the contacts 20 and 14, being thereby placed in series with one-half of the primary winding between the terminals 10 and 12. The resistance and inductance of the winding 26 are made sufficiently high so that the current flow through the primary winding is a relatively small percentage of the main energizing current provided when the contacts close.

With the arrangement shown it will be seen that as the armature 28 is moved toward the core 27, the contacts 20—21 and 14—24 close, thereby energizing one-half of the primary winding with full voltage and forming a short circuit across the winding 26, thereby causing the armature to spring back and to engage the contacts 19—21 and 13—24, thereby energizing the primary winding in the opposite direction and at the same time reenergizing the vibrator winding 26, when the cycle is repeated.

The primary circuit 15—16 is suitably loaded 55

- by a shunt capacitor 30, and a connection 35-36 is provided between two series connected capacitors 31 and 32 across the primary with the supply lead 18, whereby the capacitors are alternately connected in shunt with the primary circuit as the contacts close and in series across the primary with the contacts open to better control the contact voltage and to reduce sparking.
- 10 From the foregoing description, it will be seen that, by connecting the end terminals of a center-tapped primary winding for a vibrator transformer with one pair of oppositely disposed contacts in a vibrator mechanism, and by connecting another and similar pair of oppositely disposed contacts to one side of the supply line, while the opposite side thereof is connected to said center tap, a contact device bridging between the two sets of contacts, such as the end 15 20 of a vibratory armature or reed, may operate wholly ungrounded and without external circuit connection and at the same time may provide two air gaps in series in each side of the primary circuit for breaking the current without arcing 25 and without increasing the width of the air gap over that which is necessary or desirable for a predetermined high speed of operation, and that the speed of the break is doubled by this arrangement.
- 30 Furthermore, it will be seen that this contact arrangement is adapted readily for use in connection with the vibrator magnet or motor winding to operate on the short-circuit principle, the terminals of the winding being connected between one contact of each set on the side of the armature toward which the said armature is actuated by the magnet or motor means.

I claim as my invention:

1. In a vibrator power supply system, a vibrator device comprising a vibratory armature element, means for supporting and insulating said element adjacent one end thereof, contact means adjacent the opposite end thereof providing fixed contacts and a movable bridge connection therebetween, said contacts being spaced from the armature element to provide two series-connected air gaps, a power supply device comprising a winding, and a power supply circuit connected with said winding through said series-connected air gaps and contacts.
2. In a vibrator power supply circuit, a vibrator device for interrupting a portion of said circuit comprising an insulated vibratory reed having a free end, means providing two sets of contacts connected with said circuit and associated with said end of the reed on opposite sides thereof and in spaced relation thereto to provide four air gaps, two on each side of the reed in series in said circuit, which are alternately closed by vibratory movement of the reed thereby to provide a rapid make and break of said circuit and to reduce arcing at the contacts.
3. In a vibrator power supply circuit, a vibrator device for interrupting a portion of said circuit comprising an insulated vibratory reed having a free end, means providing two sets of contacts connected with said circuit and associated with said end of the reed on opposite sides thereof and in spaced relation thereto to provide four air gaps, two on each side of the reed, which are alternately closed by vibratory movement of the reed thereby to provide a rapid make and break of said circuit and to reduce arcing at the contacts, an actuating magnet for said vibrator armature of attracting the armature in a pre-

determined direction and said winding being connected with one each of said sets of contacts bridged by the armature when attracted in said direction.

4. A vibrator circuit comprising in combination a transformer having an operating winding, a vibratory armature member having a free end provided with contact means, fixed contact means associated with said last-named contact means providing therewith a pair of contacts on each side of the armature member bridged by said member in movement and a pair of series-connected air gaps, and a potential supply circuit for said winding connected therewith through said contact means and said series-connected air gaps, thereby to interrupt a current flow to said winding at potentials across each air gap less than the supply potential.

5. In a vibratory power supply circuit including a transformer having an input winding, the combination of a vibrator device having a vibratory armature member, means for supporting and insulating said member at one end thereof, contact means adjacent the opposite free end thereof, fixed contact means associated with said first-named contact means to provide pairs of contacts alternately bridged by said armature element in movement and a pair of air gaps in series, and means providing a circuit connection through said series-connected air gaps for said winding to make and interrupt circuit connections therethrough at relatively high supply voltages without arcing at the contacts.

6. A vibrator circuit comprising in combination a transformer having a winding provided with end terminals and a center tap, a vibratory reed having a free end provided with contact means, a pair of oppositely disposed fixed contacts between which the contact means of said reed is located to provide an air gap with respect to each contact, said contacts being connected with the terminals of said winding, a power supply circuit having one side thereof connected with said center tap, a second pair of oppositely disposed contacts associated with said free end of the reed and the contact means thereon to provide an air gap with each of said contacts, and means providing a power supply connection with each of said last-named contacts.

7. A vibrator circuit comprising in combination a transformer having a winding, a supply circuit for energizing said winding, a vibratory armature element having a free end provided with contact means, means providing a pair of contacts on opposite sides of said armature associated with said first-named contact means and connected between said supply circuit and said winding to provide a pair of series-connected air gaps effective in said circuit to interrupt current flow to said winding, said contact means of the vibratory armature element providing a bridge element movable to contact said pairs of contacts alternately, thereby to energize said winding and to make and break the current through a pair of air gaps in series, thereby to increase the speed of the break and to reduce the potential across each gap below the total potential of the supply circuit.

8. In a vibrator power supply circuit, a vibrator device for interrupting a primary current comprising a vibratory reed having a free end, means providing two sets of contacts associated with said end of the reed on opposite sides thereof and in spaced relation thereto to provide four air gaps, two on each side of the reed, which are alternately closed by vibratory movement of the reed thereby to provide a rapid make and break of four air gaps, two on each side of the reed, which are

- alternately closed by vibratory movement of the reed thereby to provide a rapid make and break of the primary circuit and to reduce arcing at the contacts, said primary circuit having terminals connected to the contacts constituting one oppositely disposed pair, a power supply circuit having one side thereof connected with the remaining oppositely disposed pair of contacts and having the opposite side of said circuit connected 10 with said primary circuit, said last-named connection being substantially a center tap connection whereby full wave operation of the primary circuit is effected by operation of the vibrator device and whereby said vibrator armature provides a movable bridge connection between the two sets of contacts without external circuit connection thereto.
9. The combination of a power supply circuit, a vibrator device and a transformer having a winding connected with said power supply circuit through said vibrator device, means providing a connection for said power supply circuit on said winding intermediate between the terminals thereof, a pair of contacts in said vibrator device connected with the terminals of said winding, a pair of series-connected capacitors connected
- across said winding and between said contacts, a second pair of contacts connected with the opposite side of said power supply circuit and with a point between said series-connected capacitors, a vibratory armature element having a free contact end and a fixed insulated end, said contact end being located between said pairs of contacts as a movable bridging element with relatively narrow air gaps and with reduced voltage at the contacts below that of the supply circuit, and 10 motor means for said armature element comprising an operating winding connected between one contact of each pair on the same side of the armature to short-circuit said winding in the attracted position of the armature element. 15
10. In a vibrator power supply system, a vibrator device comprising a plurality of fixed contacts and a vibratory armature element providing a movable bridge connection therebetween, said contacts being spaced from the armature 20 element to provide two series-connected air gaps, a power supply device comprising a winding, and a power supply circuit connected with said winding through said series-connected air gaps and contacts. 25
